UNITED STATES PATENT OFFICE.

FRANK W. MILLER, OF CHICAGO, ILLINOIS.

APPARATUS FOR BLOWING OFF, WASHING, AND REFILLING LOCOMOTIVE-BOILERS.

1,318,786.

Specification of Letters Patent. Patented Oct. 14, 1919.

Application filed May 18, 1918. Serial No. 235,253.

To all whom it may concern:

Be it known that I, FRANK W. MILLER, a citizen of the United States, residing at Chicago, in the county of Cook and State of Illinois, have invented certain new and useful Improvements in Apparatus for Blowing Off, Washing, and Refilling Locomotive-Boilers, of which the following is a specification.

This invention relates to the general art of blow-off, washout and refilling systems for locomotives, and more particularly to such systems in which the heat of the discharged steam is utilized to heat the washout and refilling water.

The primary object of the invention is to provide a system of the character specified characterized by extreme simplicity and economy and adapted for use by railroads having a comparatively limited locomotive equipment. Another object is to provide a system in which the locomotive water and fuel tank or tender may be utilized, in lieu of the usual separate tank or hot-well, for the heating of the washout and refilling water. Another object is to provide an apparatus which may conveniently be mounted between two adjacent tracks of a roundhouse or other locomotive shed and may with equal facility serve a locomotive on either track. A further object is to provide a system in which the blowing off of the steam is facilitated through the employment of an auxiliary steam condenser interposed in the path of the steam from the boiler to the water tank and supplied, through a closed circulation system, with water from the water tank itself.

Other objects and attendant advantages of the invention will be apparent to those skilled in the art from the following description, taken in connection with the accompanying drawing forming a part of this specification, and wherein I have illustrated one practical and operative form of apparatus in which the invention may be embodied and by which it may be carried out.

In the drawing—

Figure 1 is a vertical longitudinal section through a stall of a roundhouse, showing a locomotive in side elevation therein and also showing an apparatus embodying my improved blow-off, washout and refilling system mounted upon a post or stanchion between two adjacent tracks.

Fig. 2 is a transverse section on the line 2—2 of Fig. 1.

Referring to the drawing, 5 and 5' designate a pair of railway tracks located side by side in adjacent stalls of a locomotive roundhouse or shed, one of said stalls being indicated generally at 6. Between the rails of each track is the usual pit 7 connecting with the sewer, and through which the foul water from the locomotive boiler is discharged. Between the tracks is an upright post or stanchion 8 that may conveniently form one of the supports of the roof, and on this post is mounted a bracket 9 on which is supported a condenser cylinder or tank 10, this condenser having the relation of an auxiliary to the main condenser which, in the present system, consists of the water tank of the locomotive tender indicated at 11 in Fig. 1. From the top of the condenser 10 extends a steam pipe 12 consisting of a plurality of flexibly jointed sections whereby said pipe at its outer end is adapted to be connected into the steam dome 13 of a locomotive boiler 14 located on either of the tracks 5 and 5'. From the lower end of the condenser there extends another steam pipe 15, also consisting of a plurality of flexibly jointed sections by means of which the outer end section 15' may be introduced into the water tank of the locomotive tender 11 on either of the tracks 5 and 5'. The pipe 15 may be lowered into and withdrawn from the water tank of the tender by a simple manually operated device for this purpose, which, as herein shown, consists of a rope or chain 16 connected to said pipe, passing over a pulley 17 suspended from the roof 6 and anchored at 18 to a suitable catch block or hook.

19 designates a bracket mounted on the post 8 below the bracket 9 and supporting a pump 20 and an electric motor 21 for driving the pump. A hose 22 connected to the intake side of the pump is adapted at its outer end to be coupled to the discharge nozzle 23 of the water tank of the tender. A pipe 24 connected to the discharge side of the pump has two branches, one of which designated by 25 leads into the upper end of the condenser 10, while the other, designated by 26 has coupled thereto a washout and refilling hose 27 of sufficient length to serve a locomotive on either of the adjacent tracks 5 and 5'. Manually operable valves or cocks 110

28 and 29 are interposed in the branch pipes 25 and 26, respectively, by which the discharge from the pump can be directed through either of the said pipes at will.

- 5 In the operation of the present system, a locomotive having been run into one of the stalls to approximately the position shown in the drawing, the upper steam pipe 12 is connected into the steam dome 13 and the 10 lower steam pipe 15 is lowered into the water tank of the tender 11, as shown. The hose 22 is also connected to the discharge nozzle 23 of the tender, the valve 29 is closed and the valve 28 is opened, and the pump 20 is 15 started in operation. The steam in the boiler blows off through the pipe 12, condenser 10, and pipe 15 into the water contained in the water tank of the tender 11, thereby imparting its heat to the latter. At 20 the same time the water in the water tank is circulated by the pump 20 through the condenser 10, by which the steam is partially condensed on its way to the water tank, and its heat more effectively and thoroughly 25 transferred to the water, it being noted that there is a continuous closed circulation of the water in the water tank while the steam is blowing off.

As soon as the blowing off of the steam 30 is substantially completed, the usual drain cock on the under side of the boiler is opened above the pit 7, and the dirty water and accumulations of scale and sludge are discharged into the trough and thence to the 35 sewer. As soon as the boiler is emptied, the valve 28 is closed, the valve 29 is opened, and thereupon the pump 20 operated to force the heated water from the tank of the tender through the hose 27 the nozzle of 40 which is inserted into the various hand holes of the boiler to thoroughly wash out the boiler. This operation is continued until the boiler is thoroughly washed out, after which the boiler drain cocks and hand holes 45 are closed, and the hose is inserted into or connected with the boiler above the water line so that the boiler is refilled by the heated clean water from the tender tank.

It will be observed that both the apparatus for and method or operation of blowing off, washing and refilling the locomotive herein shown and described are extremely simple and easy of manipulation, and involve comparatively slight expense of construction and installation. By utilizing the water tank of the locomotive tender as the means for conserving the heat of the blow off steam and also as the source of supply of the washout and refilling water, considerable economy is effected over more elaborate systems where a special tank for this purpose is provided. The use of the condenser 10 is not essential, but the same is preferably employed as constituting a helpful auxiliary to the water tank itself

which, of course, performs the function of the main condenser. It will also be manifest that by making the steam and water conductors flexible as shown, a single installation is equally well adapted to serve locomotives on either of the two tracks between which the apparatus is installed. 70

It is believed that the foregoing and other advantages of the invention will be readily understood and appreciated by those familiar with systems of this character from the foregoing, without further description. The details of construction and arrangement illustrated and described are, of course, capable of considerable modification and 80 variation without departing from the substance and scope of the invention as defined in the following claims. 75

I claim:

1. In a locomotive blow-off, washing and 85 refilling system, the combination of a steam condenser located adjacent a track, a flexibly jointed steam pipe leading from said condenser and adapted to be connected into a boiler of a locomotive on said track, another flexibly jointed pipe leading from said condenser and adapted to be entered into the water tank of a locomotive tender on 90 said track, a pump, an intake pipe for said pump adapted to be connected to said water tank, and a connection from the discharge side of said pump to said condenser. 95

2. In a locomotive blow-off, washing and 100 refilling system, the combination of a steam condenser located between adjacent tracks, a pipe adapted to conduct blow-off steam 105 from a locomotive on either of said tracks to said condenser, a pipe adapted to deliver steam and water from said condenser below the water level in the tank of a tender on either of said tracks, a pump, an intake pipe 110 for said pump adapted to draw water from the tank of a tender on either of said tracks, and a connection between said pump and said condenser for delivering water from the pump to said condenser. 115

3. In a locomotive blow-off, washing and 115 refilling system, the combination of a condenser located adjacent a locomotive pit, a pipe adapted to deliver blow-off steam 120 from a locomotive to said condenser, a pipe connected with said condenser and adapted to be introduced into the water tank of a locomotive tender through which steam and water are delivered from said condenser to 125 said tank, a pump, an intake pipe for said pump adapted to be connected to said tender tank, a branched delivery pipe from said pump, a connection between one of said branches and said condenser, and a washout 130 hose connected to the other branch.

4. In a locomotive blow-off, washing and 130 refilling system, the combination with a suitable support located between adjacent tracks of a roundhouse, of a steam condenser

mounted on said support, a flexibly jointed steam pipe leading from said condenser and adapted to be connected into the boiler of a locomotive on either of said tracks, 5 another flexibly jointed steam pipe leading from said condenser and adapted to be entered into the water tank of a locomotive tender on either of said tracks, a pump mounted on said support, a hose connected to the intake side of said pump and adapted for connection to said water tank, and a pipe connection from the discharge side of said pump to said condenser.

5. In a locomotive blow-off, washing and 15 refilling system, the combination with a suitable support located between adjacent tracks of a roundhouse, of a steam condenser mounted on said support, a flexibly jointed steam pipe leading from said condenser and adapted to be connected into 20 the boiler of a locomotive on either of said tracks, another flexibly jointed steam pipe leading from said condenser and adapted to be entered into the water tank of a locomotive tender on either of said tracks, a pump 25 mounted on said support, a hose connected to the intake side of said pump and adapted for connection to said water tank, a pipe connection from the discharge side of said pump to said condenser, a washout and refilling 30 hose also connected to the discharge side of said pump, and valves in said last-named hose and said pipe connection whereby the discharge from the pump may be directed through either.

FRANK W. MILLER.
